SHUTTLE CHECK CONTROLLED BY
TEMPERATURE

Richard G. Turner, Worcester, Mass., assignor to
Crompton & Knowles Loom Works, Worcester,
Mass., a corporation of Massachusetts

Application December 15, 1944, Serial No. 568,305

12 Claims. (Cl. 139—185)

This invention relates to improvements in shuttle checks for looms and it is the general object of the invention to provide shuttle checking mechanism the checking effect of which varies with temperature changes thereof.

After a loom has stood idle overnight several minutes of operation are required to establish proper running condition due principally to the fact that the parts of the shuttle box which engage the shuttle are cold and have the effect of causing the binder or other checking agent to exert too great a force on the shuttle. The latter is therefore not able to enter the shuttle box to a sufficient depth for correct picking and the protector mechanism operates to stop the loom. After a short period of this unsatisfactory operation the shuttle box temperature is raised sufficiently so that thereafter the shuttle runs smoothly and does not interrupt operation.

It is an important object of my present invention to provide a shuttle checking mechanism which is responsive to changes in temperature and which acts in such a way as to offer a reduced or subnormal checking force to the shuttle when cold and offer a higher or normal checking resistance when warm. As set forth hereinafter I accomplish these results by making the shuttle binder of two different metals having different coefficients of expansion and wherein the metals are related so that as the binder temperature rises it will be bent or curved toward the shuttle.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a front elevation of one end of a loom having a binder made according to my present invention.

Fig. 2 is an enlarged plan view looking in the direction of arrow 2, and

Fig. 3 is an enlarged plan view of the binder shown in Fig. 2 showing how its contour is changed by alteration of its temperature.

Referring particularly to Fig. 1, I have shown a loom frame 10 having a lay 11 with a shuttle box 12 at the right end thereof. A picker stick 13 is provided with a picker 14 for picking the shuttle S out of box 12, and picking mechanism designated generally at 15 is connected to the stick in usual manner as at 16. The shuttle box 12 may have a box back 20 fixed to the lay as suggested in Fig. 2 and has a binder pivot or pin 21 and the usual binder spring 22.

The matter thus far described is of common construction and of itself forms no part of my present invention.

In carrying my present invention into effect I provide shuttle checking means which exerts a varying checking force on the shuttle depending upon the temperature of the checking means. As set forth herein the invention is applied to a shuttle binder, but I do not wish necessarily to be limited to this means of carrying my invention into effect.

Referring to Figs. 2 and 3 it will be seen that the binder B is pivoted on pin 21 and has the left end thereof received by a guide 23 forming part of the box mouth 24. The binder is made of two strips of metal having different coefficients of expansion, the outer or front strip 25 having a relatively low coefficient while the inner or rear strip 26 has a higher coefficient. These two strips may be secured together in any approved manner as by brazing so that heat will be transmitted readily from one strip to the other and the two strips in effect will form a single integrated binder. In practice I have made the strip 25 of steel and the strip 26 of brass and have secured the two parts together by means of silver solder.

When the loom is started up after a considerable period of inactivity both the strips 25 and 26 will be cold and the binder as a whole will be of such form that there is a maximum distance between the box back 20 and the shuttle checking surface 27 of the binder. Under these conditions the binder will have a form suggested by the full lines in Fig. 3 and offers a minimum of resistance to the shuttle, a condition which is favorable to the picking of a cold shuttle. As picking continues the frictional engagement of the shuttle with the surface 27 heats up both 40 of the strips 25 and 26 and the latter strip expands slightly more than does the steel strip with the result that the contour of the binder is changed and surface 27 moves rearwardly toward the wall 20 as indicated in dotted lines, Fig. 3. 45 Under these conditions the binder offers a higher resistance to checking of the shuttle, but by this time the shuttle has become sufficiently warm so that it is adjusted to the greater checking force of the shuttle binder. The aforesaid higher checking resistance will in fact be the normal resistance of ordinary operations, while the lower resistance offered when the binder is cold will be subnormal.

In some cases it may be desirable to provide 50 the brass strip 26 with a protective coating to

prevent discoloration of the front wall of the shuttle. For this purpose I have sprayed the rear surface of the strip 26 with stainless steel, after which the sprayed surface is polished. The spraying leaves only a thin layer of metal on the brass strip which has little or no effect in counteracting the tendency of strip 26 to expand as the temperature thereof rises.

While I have described the binder as being made of strips of steel and brass, yet I do not wish necessarily to be limited to this combination of metals, inasmuch as it is sufficient for the purposes of my invention if the binder is so constructed that its contour changes as its temperature rises. Any two metals having different coefficients of expansion can be used. Thus, the strip 26 can be replaced by a strip of ordinary steel, while the strip 25 can be made of a metal known in the trade as Invar and having a practically negligible coefficient of expansion. Whatever selection of metals is employed it is desirable that the one having the higher coefficient of expansion is placed nearest to the shuttle so that as the temperature of the composite binder rises its shuttle checking surface will be bowed rearwardly to increase the shuttle checking effect.

From the foregoing it will be seen that I have provided a shuttle checking mechanism for a loom so constructed as to be responsive to temperature changes in such a way that as the temperature rises the shuttle checking resistance is increased.

Having thus described my invention it will be seen that changes and modifications may be made therein by those skilled in the art without departing from the spirit and scope of the invention and I do not wish to be limited to the details herein disclosed, but what I claim is:

1. In a loom having a lay provided with a shuttle box into and from which a shuttle is picked, shuttle checking means forming part of the shuttle box and formed of two metallic parts extending along and secured to each other and having different coefficients of expansion; said checking means being positioned for frictional engagement with the shuttle so that the temperature of said metallic parts rises with continued operation of the shuttle; said checking means being so constructed that as the temperature thereof rises the checking effect thereof on the shuttle is increased.

2. In a loom having a shuttle box into and from which a shuttle is picked, a shuttle checking member forming part of the shuttle box and constructed of two metallic parts secured to each other and having different coefficients of expansion, said member being positioned for engagement with the shuttle and effective as the temperature thereof rises due to frictional engagement with the shuttle to increase the checking effect thereof on the shuttle.

3. In a thermally controlled shuttle checking mechanism for a loom having a shuttle box into and from which a shuttle is picked, a member positioned for engagement with the shuttle to check the latter and formed of two metallic parts having different coefficients of expression and responsive to changes of temperature thereof in such manner as to increase the shuttle checking force exerted by the member on the shuttle as the temperature of the member increases.

4. In a loom having a lay provided with a shuttle box, a box forming wall extending along one side of the shuttle box, and a binder pivoted to

the lay and extending along the other side of the box, said binder having a shuttle engaging surface bowed toward the wall, and said binder being made of two metallic parts secured to each other and having different coefficients of expansion, said parts being so related that as the temperature thereof increases said surface moves toward said wall.

5. In a loom having a lay provided with a shuttle box, a box forming wall extending along one side of the shuttle box, and a binder pivoted to the lay and extending along the other side of the shuttle box and having a shuttle engaging surface bowed toward said wall, said binder being formed of two pieces of metal having different coefficients of expansion which operate upon a rise of temperature of the binder to move said surface toward said wall.

6. A thermally controlled shuttle checking mechanism for a loom including a shuttle engaging member made of two parts having different coefficients of expansion and so constructed as to exert a subnormal checking force on the shuttle when the temperature of the mechanism is subnormal and exert normal checking force on the shuttle when normal operating temperature of the mechanism is attained.

7. A thermally controlled shuttle checking mechanism for a loom including a shuttle engaging member made of two parts having different coefficients of expansion and so constructed as to exert a relatively small checking force on the shuttle when the temperature of the mechanism is relatively low and exert a large checking force on the shuttle when the mechanism is at a higher temperature.

8. A loom shuttle binder having a shuttle engaging surface and formed of two members having different coefficients of expansion, said members being so related that the contour of the shuttle engaging surface of the binder is altered as the temperature of said members increases.

9. A loom shuttle binder having a shuttle engaging surface between the ends thereof and formed of two members having different coefficients of expansion, said members being so related that said surface moves away from a line joining the ends of the binder as the temperature of said members increases.

10. In a loom having a shuttle box, a binder forming part of the shuttle box and including a strip of metal having a relatively low coefficient of expansion on the outer side of the binder facing away from the shuttle box and including a second strip of metal secured to the first strip and having a relatively high coefficient of expansion and located on the inner side of the binder facing toward said shuttle box.

11. In a loom having a shuttle box, a binder forming part of the shuttle box and including a strip of steel located on the side of the binder facing away from the shuttle box and said binder including also a strip of brass secured to the first strip and located on the side of the binder facing toward the shuttle box.

12. In a loom having a shuttle box, a binder forming part of the shuttle box and including a strip of metal having a relatively low coefficient of expansion located on the side of the binder facing away from the shuttle box and said binder including also a strip of metal having a relatively high coefficient of expansion secured to the first strip and located on the side of the binder facing toward the shuttle check.
